UNITED STATES PATENT OFFICE

CLARK F. RIGBY, OF BUTLER, PENNSYLVANIA, ASSIGNOR TO WILLIAM H. LARKIN, JR., OF BUTLER, PENNSYLVANIA

OIL SAVER

Application filed October 6, 1927. Serial No. 224,333.

This invention relates to an oil saver.

To prevent the escape of oil and gas during the drilling of a well, and after a productive sand has been reached, it is necessary to close the opening in the casing head through which the drilling cable passes. A number of devices have previously been designed and used for this purpose, among such being those illustrated and described in the patents granted to the present inventor, No. 696,747, dated April 1st, 1902, No. 983,314, dated February 7th, 1911, and No. 1,152,548, dated September 7th, 1915.

One object of the invention is to provide an oil saver which may be readily removed from the casing head and drilling cable in connection with which it is used.

Another object of the invention is to provide an improved seat between the casing head and oil saver, and to provide a washer for use in this seat which is so arranged as to positively prevent leakage therewith.

A further object of the invention is to provide a washer or packing around the drilling cable, which will engage the drilling cable tighter as the pressure in the casing rises, thereby positively preventing the escape of gases in this region also.

In the drawings Figure 1 is a side elevation of the device of the present invention mounted on a casing head; Figure 2 is a sectional view taken on the line 2-2 in Figure 1; Figure 3 is a top plan view of the split packing gland; Figure 4 is a fragmentary view in cross section, showing the novel seating washer in its normal position; Figure 5 is a similar view showing the washer's position when pressure exists in the casing; Figure 6 shows a modified form of cable packing; Figure 7 is a similar view showing the effect of pressure within the casing.

With reference to the drawings, 1 designates a well casing, 2 a casing head, and 3 a casing head collar which is fixed in the casing head by means of set-screws 4. In the collar 3 is fixed the washer 5, which washer is composed of any suitable resilient material. The said washer is formed with an annular V notch 7. Threaded sleeve 6 serves

to maintain the washer rigidly in its track. As shown in Figures 2, 4, and 5 of the drawings, the open edge of the V notch faces the seam 9 between the collar 3 and the oil saver head 8. When there is little or no pressure in the casing there is no tendency for the gas or oil to pass up the seam 9 and escape. The position of the washer 5 as illustrated in Figure 4 shows how the lip 5a of washer 5 tends to fall away from the seating shoulder 10 when there is no appreciable pressure in the casing pipe. When, however, a pressure builds up in the casing there is a tendency for the fluid to work its way up the seam 9. As can readily be seen from the drawings the said line of escape terminates in the V notch 7, and any pressure in the casing causes the lip 5a to seat tighter against the shoulder 10. This is shown in Figure 5. In this manner the seating between the collar 3 and head 8 becomes tighter as the pressure in the casing increases.

The means of attaching the oil saver head 8 in the collar 3 are practically the same as those employed in the Patent No. 1,152,548, dated September 7, 1915. That is, a plurality of latches 11 engage the collar 3 as shown in Figure 2. In the drilling operation the process of withdrawing the drilling tools is simplified, owing to the function of members 12. When the drilling cable C is drawn upward the tool holder 13 strikes members 12 which cause the latches 11 to move inwardly to allow the head 8 to rise with the cable. The operation of the latter mechanism is described in detail in the last cited patent.

In the previous forms of oil savers, it was found difficult to remove the head 8 from the drilling cable. To overcome this obvious inconvenience the new form of split head was designed. The head 8 is composed of two halves 8a and 8b respectively, each half being commonly hinged at 14. A pivoted bolt 15 and wing nut 16 serve to hold the two halves together in operating position around the drilling cable C. Each half of the head 8a and 8b has a handle 8c and 8d respectively. The purpose of the handles is to

facilitate the handling of the split head 8 in removing or replacing the same on the drilling cable C. It should be understood that the arrangement of said handles is of prime importance. The handles pass outwardly at an angle from the joining edges of the two head portions 8a and 8b. This allows one man to fit the head on the cable and press the two handles together with one hand while the wing nut 16 is positioned and tightened with the other hand.

In Figure 2 the usual manner of packing is illustrated at 17. The packing material is caused to engage closely the drilling cable C by means of the packing T gland 18 which may be screwed down to give the proper pressure on the packing material 17. It is not novel to have the T gland in two portions, but by having the parting surface of one leg of the T rounded off at 18a it is possible to unscrew gland 18 from the head 8, and remove a nut and bolt from hole 18b, open the gland to the position shown in dotted lines in Figure 3, and remove the same as a whole from the drilling cable. This feature prevents different halves of T glands from becoming mixed, and in addition saves some manual labor in the removal of the gland from the cable.

Figures 6 and 7 illustrate a novel form of packing plug 19. The theory and operation of this plug is similar to that of the washer 5. When there is no pressure in the casing, the plug rests as is shown in Figure 6. In Figure 7 the annular lip 19a is shown fitting snugly around the cable C. Pressure in the casing is transmitted through the aperture 20 into the V space 21 in the plug 19. The pressure in the space 21 causes the lip 19a to press against the cable C in accordance with the casing pressure. The composition of this plug may be rubber of medium rigidity, or any other material of suitable characteristics.

The features of the split gland, the novel packing ring, and the split head serve to make the apparatus much more useful and desirable than the old forms of oil savers. The packing plug may be useful in many devices of a similar nature.

What I claim is:

The combination of a casing head collar having a seat therein, a washer in said seat being locked therein by a sleeve, which washer is provided with an annular groove within its inner face, an oil saver having a body extending into said sleeve, which oil saver is formed with a shoulder that rests upon the top of said washer and extends downwardly over the inner face of the washer to said annular groove.

In witness whereof, I hereunto set my hand.

CLARK F. RIGBY,
